UNITED STATES PATENT OFFICE.

WILLIAM LUMLEY, OF CHICAGO, ILLINOIS.

TEMPORARY BINDER.

SPECIFICATION forming part of Letters Patent No. 404,210, dated May 28, 1889.

Application filed October 18, 1887. Serial No. 252,693. (No model.)

To all whom it may concern:

Be it known that I, WILLIAM LUMLEY, a subject of the Queen of Great Britain, residing in Chicago, county of Cook, and State of Illinois, have invented certain new and useful

5 Improvements in Temporary Binders, of which the following is a specification.

This invention relates to improvements in temporary binders in which letter-file indices

10 are kept for ready reference while in constant use and prior to their storing or insertion into permanent files or cases—that is, after the index has been used a certain length of time or become too full for convenient

15 handling, and it also relates to that class of temporary binders that are provided with a yielding clamp or holder for maintaining the index in a smooth compact form, so as to obviate the accidental loss of papers therefrom.

20 In binders as heretofore constructed the pin for engaging the perforated tag attached to the index-sheets has been either rigidly secured to the index-frame or else removably attached thereto, in both of which cases a

25 fastening device for protecting the free end of such pin against the accidental removal of the index-sheets has been employed, and which device must necessarily be operated by hand whenever the index-sheets are re-30 moved from or inserted in position in the binder.

One of the objects of this invention is to hold the index-sheets by means of a pin pivoted to the base of the binder, so as to yield laterally from its upright position for the insertion or removal of said sheets, and to have said pin maintained in an upright position and the sheets prevented from accidental removal by means of a spring-catch which will 35 engage and hold the pin when pushed against it; also, to have the laterally-yielding pin before referred to actuated so that when released after the insertion or removal of sheets the said pin will automatically engage and 40 be locked in an upright position by its retaining-catch.

Another object is to provide a temporary binder with a yielding holder for retaining the index-sheets in position actuated by devices concealed within the binder-frame and 45 which are adapted to yieldingly retain said holder in an elevated position away from the

indices, whereby the least obstruction to the insertion of the index sheets or papers is prevented, the parts protected from injury, and 55 a better finish given to the binder as a whole.

A further object is to simplify the construction by dispensing with a number of parts heretofore employed in temporary binders, and therefore materially lessening the cost of 60 manufacture.

A further object is to so attach the index-frame to the index-holder that while free to assume a limited number of angles relative to the surface of the index-sheets it cannot 65 rotate upon its support.

A still further object is to provide means for transferring the index-sheets from the temporary binder to a permanent file without the liability of disarrangement of said sheets, 70 whereby the eyes thereof may be easily caught upon a pin in the permanent file without trouble or the employment of skill.

I attain these objects by devices illustrated in the accompanying drawings, in which— 75

Figure 1 represents a plan view of a temporary binder embodying my invention; Fig. 2, a central vertical section thereof, showing the means employed for rendering the holding-pin laterally yielding; Fig. 3, a detail side 80 elevation, partly in section, showing the construction of the yielding index-holder; Fig. 4, a detail perspective representing the preferred form of automatic catch; Fig. 5, a modification thereof, showing the catch secured to 85 the binder-frame in a different manner; Fig. 6, a detail perspective of the holding-pin and device employed for removing the index-sheets; Fig. 7, a horizontal sectional view thereof; Fig. 8, a detail view showing a modification of the means employed for preventing a rotation of the index-frame; Fig. 9, a similar view of a second modification; Fig. 10, a plan view thereof; Fig. 11, a detail view of a portion of an index-sheet, showing the 90 95 perforated tag attached thereto for engaging the holding-pin.

Referring by letter to the accompanying drawings, A indicates the back, and B the sides, of an ordinary binder-frame attached 100 to a base-board, C, as usual, so as to leave one end thereof open, no drop-cover being necessary in a binder of this class, in which an index-holder is employed, the construction and

operation of which will be hereinafter more fully described.

To the base-board C, about the center of length thereof, but near the back, is pivoted 5 in an upright position an index-sheet holding-pin, D, the lower end of which is turned at substantially a right angle, so as to form a foot, E, along the under side of which lies the free end of a flat spring, F, the opposite end 10 of which is secured to the base C. This spring and the foot of the pin work in a recess, G, formed in the base C, which recess is concealed from view, preferably, by metallic covering-plate H, upon which is cast depending 15 ears or lugs I, constituting the bearings in which the pin D is pivoted. It is obvious that whenever the pin, or rather the upper free end thereof, is pulled forward, so as to depress the foot thereof, the flat spring will yield under tension; but when the pin is released the 20 spring which constitutes a yielding support therefor will cause the pin to immediately return to and remain in its normal upright position until again deflected by force.

25 In order to prevent the weight of the index-sheets, or any other unintentional force, from laterally deflecting the holding-pin, and thereby endanger the accidental dislodgment of said sheets, I provide a spring-catch, J, secured at one end to the back of the binder and having its opposite free end projecting over the end of the holding-pin, which latter projects through a hole, K, formed in the end thereof.

35 The end of the pin has a notch, D², formed on the rear side thereof, which is designed to receive the catch when the end of the pin projects through the hole in said catch. The tension of the spring F operating to cause the 40 end of the pin to bear against the rear edge of said hole, consequently the end of the pin hooks over the catch and prevents the upward pressure of a crowded file from accidentally releasing said catch. The automatic 45 insertion of the end of the pin in the hole may be materially aided by slightly upturning the forward edge of the spring-catch, so that the end of the pin will pass under and elevate the same by its own action. This spring-catch 50 may vary both in form and construction, the simplest form preferably being shown, consisting of a flat spring, which may either be twisted and secured to the inner face of the back or may be countersunk into the top edge 55 thereof, all as shown in Figs. 5 and 6.

For the purpose of holding the filed papers flat and in a compact body secure from accidental loss, I provide a yielding index-holder consisting of the flat metallic bail L, upon 60 which is mounted a rectangular wire index-frame, M, for bearing directly upon the index-sheets. This frame may, if desired, be rigidly secured to the bail; but it is preferable to pivot the same thereto, in order that the 65 said frame may adjust itself to the differing planes of the index-sheets, which may vary according to the quantity of paper filed be-

tween them; but it is not desirable that this frame should be free to rotate upon its pivot, as is common in this class of devices, because 7c the frame often turns partially or completely over when elevated above the index-sheets, and unless reversed will come down on the papers upside down, causing considerable annoyance and loss of time by its frequent recurrence. For this reason I have connected the frame with the bail by means of offset portions N of said frame, the horizontal parts of which pass through the holes N', formed in the bail L above the center of width 80 thereof, in such manner that the shoulders N² at the conjunction of the offset portion with the main frame will engage the lower edge of the said bail and thereby prevent a rotation of said bail upon the frame, although permitting considerable vibration thereof, for the purpose hereinbefore stated.

In Figs. 8, 9, and 10 are illustrated modified means for accomplishing this same object, the index-holder in both of these cases consisting 90 of side arms, a, connected at their outer ends by the cross-rod b, upon which is mounted, by looping or winding thereon, the rectangular frame c for holding the index-sheets.

The means shown in Fig. 8 for preventing 95 a rotation of the index-frame are laterally-projecting ears d d, formed on the side arms, a, between which the said frame is confined, but is free to vibrate, while in Figs. 9 and 10 a projecting end, e, of the index-frame is 100 shown as engaging a curved slot, f, formed in a depending portion, g, of the side arm, a, which also permits the same vibration of the frame upon its pivot, but prevents a rotation thereof. Hence it will be seen that I do not 105 desire to limit myself to the particular means herein shown and described for preventing a rotation of said frame upon its pivot, for various devices may be employed for accomplishing the same end.

The ends of the bail L have secured thereto short pivot-pins O, which pass through covering-plates P, and have rigidly secured to the opposite ends thereof short crank-arms Q, working in recesses R, formed in the sides 115 B of the binder, in which recesses also work spiral springs S, secured at one end to the crank-arm Q, and at their opposite ends to the covering-plates P, which latter serve the double purpose of a bearing-plate for the 120 pivots and springs and as covering-plates for the recesses in the sides. The side and crank arms are so disposed relative to each other and the point of attachment of the springs S that the tension of said springs acting upon 125 the arms at an angle thereto operate to maintain the index-holder in close contact with the index-sheets by exerting a downward pressure upon said arms, which pressure will continue in force until the holder and consequently the crank-arms are sufficiently elevated to bring the ends of the springs and the pivot of the holder to a dead-center, at 130 which time the tension of the springs is ex-

erted in a line parallel with the crank-arms; but when the crank end of the spring passes beyond such center the tension of such spring will come into play to yieldingly maintain 5 the holder in its elevated position until again depressed by force, as clearly shown in Fig. 2 of the drawings.

In practice, when the binder becomes sufficiently filled, it is transferred to a permanent 10 file, generally provided with a fixed holding-pin for engaging the eyes of the index-sheets, and it is desirable at such a time to hold the sheets in the act of transferring, so as to prevent a shifting thereof; otherwise difficulty 15 may be encountered in causing the eyes to engage the pin. To this end is provided the transfer device shown in Fig. 6, consisting of a small disk or head, *h*, having two guide-pins, *i*, depending therefrom for engaging 20 corresponding peripheral grooves, *j*, formed longitudinally in the sides of the holding-pin *D*, the said device being designed to be passed through the eyes of the index-sheets while engaged by the holding-pin and to be stripped 25 from said pin simultaneously with the index-sheets, thereby retaining said sheets in the same position with all the eyes in exact alignment, thus facilitating the engagement of said eyes with the pin on the permanent 30 file.

It is obvious that the two pins being set apart a distance equal to the diameter of the holding-pin, the eyes which fit the latter must be held in exact alignment by said pins when 35 withdrawn from said holder; and it is immaterial, so far as concerns this portion of my invention, whether the holding-pin be fixed or yielding.

In a device constructed as just described 40 there is embodied the three essential elements of a device of this character—namely, simplicity, durability, and economy—in addition to which the actuating mechanisms are concealed from view, and at the same time 45 protected from injury or unnecessary wear occasioned by the lodgment therein of dust or other foreign substances.

Having described my invention, what I claim, and desire to secure by Letters Patent, 50 is—

1. The binder-frame, in combination with a holding-pin normally perpendicular to the bottom of said frame, and a pivot-connection

between said frame and pin, whereby said pin may be deflected laterally to receive the index-sheets, substantially as and for the purpose described. 55

2. The binder-frame, in combination with a holding-pin normally perpendicular to the bottom of said frame, a pivot-connection between said frame and pin, and a catch device 60 on the arm of said frame for engaging the free end of said pin and locking the pin in its upright position, substantially as described.

3. The binder-frame, a holding-pin perpendicular to the bottom of said frame, and a pivot-connection between said frame and pin, in combination with a spring actuating the pin resisting a lateral deflection thereof, whereby said pin will be automatically returned to its normal position when released, 70 substantially as described.

4. The binder-frame, a holding-pin normally perpendicular to the bottom of said frame, and a pivot-connection between said 75 frame and pin, in combination with a spring engaging said pin, so as to resist a lateral deflection thereof, and a spring-catch secured to the rim of said frame and arranged to be automatically engaged by said pin, substantially as described.

5. In a temporary binder, the holding-pin provided with longitudinal peripheral grooves, in combination with a disk or head and pins secured to said head for engaging said grooves, 85 substantially as described.

6. In a temporary binder, the index-holder, in combination with the index-frame, a pivot-connection between said frame and holder, and a stop device for preventing a reversal of 90 the operative face of the index-frame with reference to the index-sheets, but permitting a vibration of said frame upon its pivots, substantially as described.

7. In a temporary binder, the index-holder 95 consisting of a flat metallic bail provided with perforations therein, in combination with the index-frame and offset, portions of said frame passing through and working in said perforations and constituting a stop device for said index-frame, substantially as described. 100
